UNITED STATES PATENT OFFICE.

WILLIAM M. BAGO, OF HAMILTON, OHIO.

RAILWAY CROSSING.

Application filed October 4, 1924. Serial No. 741,718.

To all whom it may concern:

Be it known that I, WILLIAM M. BAGO, a citizen of the United States, residing at Hamilton, in the county of Butler and State 5 of Ohio, have invented new and useful Improvements in Railway Crossings, of which the following is a specification.

The object of my invention is to provide a simple, efficient and durable railway crossing, and one which is secured to the rails alone and hence is adapted to be removed and repaired with facility and as readily replaced and secured in position.

To the attainment of the foregoing, the 15 invention consists in the improvement as hereinafter described and definitely claimed.

In the accompanying drawings, forming part of this specification:—

Figure 1 is a plan view showing the cross- 20 ing constituting the preferred embodiment of my invention.

Figure 2 is a side elevation of the same.

Figure 3 is an enlarged detail cross-section taken in the plane indicated by the line 25 3—3 of Figure 1.

Figure 4 is an enlarged detail section showing a portion of my improvement in inverted plan.

Figure 5 is a detail section taken in the 30 plane indicated by the line 5—5 of Figure 1.

Similar numerals designate corresponding parts in all of the views of the drawings.

I illustrate in Figures 1 and 2 the rails 1 of a railway, and by reference to Figure 1 35 it will be understood that my novel crossing comprises frame sections 3 located between the rails and flush with the treads thereof and frame sections 4 located outside the rails and opposite the sections 3, the frame 40 sections 4 being also flush with the treads of the rails 1 and flush with the surface 5 of a roadway. Each of the sections 3 is preferably of malleable iron and each is provided with a plurality of compartments or cells 45 6, the said cells being open at their upper and lower ends and being provided adjacent to their lower ends with flanges 7, Figure 3, and being also provided in their side walls and adjacent to their upper ends with undercut recesses 8, Figure 5. The cells 6 are 50 provided with removable bottoms 9, Figure 3, and are designed to be filled up to points flush with the upper sides of the sections with concrete or other appropriate plastic 55 material designated by 10. Manifestly by virtue of the construction described when

the sections are disconnected and removed they may be inverted, and a rod may be employed to displace the bottoms 9 and the concrete 10, after which the bottoms 9 may 60 be replaced in the cells and the cells may be charged with fresh concrete or other appropriate plastic material. In this manner the sections can be expeditiously and easily repaired with a view to prolonging the usefulness of the crossing.

As shown in Figures 1 and 5 the sections 3 and 4 are provided by preference with inclined skirt flanges 11. It will also be readily understood that the sections are provided in their corner portions near the rails 1 with countersinks 12, designed to receive nuts on bolts 13. The sections 3 and the sections 4 have flanges 14 and 15, respectively, designed to bear on the rail bases in 75 the manner clearly shown in Figure 3; it will also be noted that the corners of the sections 3 adjacent to the heads of the rails 1 are recessed as designated by 16 in Figure 3 to afford clear passages for the flanges of 80 wheels. The opposed edge portions of the sections 3 are detachably connected together by bolts 17 and nuts 18, Figure 1, and the opposed edges of the sections 4 are similarly connected together as illustrated in Figure 1.

The sections 3 and 4 are connected with the rails 1 and are held down to their work by the said rails 1, and from this it follows that the removal of the sections 3 and 4 is 90 not attended by any disconnection of the same from the ties of the railway. This will be better understood when it is stated that my improvement includes coupling bodies 19, preferably of malleable iron, 95 which rest transversely below and receive the rails 1 and are connected by the bolts 13 and complementary nuts with the sections 3 and 4 so as to strongly connect the said sections together and to the rails 1. In 100 the latter connection it will be noted that the coupling bodies 19 bear solidly against the undersides of the sections 3 and 4.

It will be apparent from the foregoing that my improvement constitutes a crossing 105 which is smooth and durable, is susceptible of being readily installed, and is adapted when wear of the concrete or other plastic material takes place to be expeditiously and easily repaired.

I have specifically described the preferred embodiment of my invention in order to im-

part an exact understanding of said embodiment. I do not desire, however, to be understood as confining myself to the specific construction and relative arrangement of parts inasmuch as my invention is defined by my appended claims within the scope of which changes may be made without involving departure from my invention.

Having described my invention, what I claim and desire to secure by Letters-Patent, is: —

1. In a railway crossing, a frame having cells open at their upper and lower ends, and plastic material in said cells, said cells provided in the lower portions thereof with means for supporting said plastic material.
2. In a railway crossing, a frame having cells open at their upper and lower ends and also having flanges near the lower ends of the cells, in combination with bottoms removably arranged in the cells and on said flanges, and plastic material arranged in the cells and on said bottoms.
3. In a railway crossing, a frame having cells open at their upper and lower ends, and plastic material supported in the said cells;

the said cells having undercut recesses in their side walls to key the plastic material to said walls.

4. The combination in a railway crossing of a frame having cells with undercut recesses in their side walls and with interior flanges adjacent to their lower ends, said cells being open at their upper and lower ends, bottoms removably arranged in the cells and on said flanges, and plastic material in the cells and on said bottoms and keyed by said recesses to the frame.

5. In a railway crossing and in combination with the rails of a railway, metallic frame sections disposed at opposite sides of the rails and each including a frame having a plurality of cells, and plastic material occupying the said cells, said frames arranged flush with the treads of the rails, coupling bodies arranged transversely under the rails, and connections between said coupling bodies and sections and having upper portions disposed in countersinks of the sections.

In testimony whereof I affix my signature.

WILLIAM M. BAGO.
